UNITED STATES PATENT OFFICE.

THOMAS E. COLLINS, OF CHICAGO, ILLINOIS.

FIRE-DOOR.

1,149,732.

Specification of Letters Patent. Patented Aug. 10, 1915.

Application filed August 24, 1911. Serial No. 645,754.

To all whom it may concern:

Be it known that I, THOMAS E. COLLINS, a citizen of the United States, residing at Chicago, in the county of Cook and State of Illinois, have invented certain new and useful Improvements in Fire-Doors, of which the following is a specification.

My invention pertains to fire doors and is particularly directed toward improving the type of fire door or shutter which comprises a rotatable drum with a curtain carried thereby.

In my conception of this invention, I have been guided by the necessity for greater simplicity in fire doors and greater surety of operation. In attaining these advances in the art, the primary step taken by me has been in the direction of creating a simpler, and yet perfectly effective, connection between the shutter drum, the counter-balancing mechanism and the base support. In other words, my aim is to provide a counter-balancing mechanism which is comparatively related to the drum and base support by a direct connection and without the necessity for any intermediate gearing. A second step toward improving the art, has taken the form of providing an operating structure formed of a minimum number of parts and which parts are practically completely inclosed within the shutter drum. The advantage of this will be apparent in the complete removal of the mechanism from the stress of weather and of excessive heat tending to warp the parts.

More specifically, my invention takes the form of a shutter mounted upon a rotatable drum which is normally maintained against a gravity fall in counter-balanced condition. The maintenance of this counter-balanced condition, however, is effected by a clutch element carried internally by the drum and by a longitudinally shiftable shaft carrying complementary clutch disks which are adapted to clutch said shaft to said disk at opposite ends of the said longitudinal movement whereby the counter-balancing means is rendered effective upon the drum at opposite points of the longitudinal movement of the shaft, but is rendered ineffective as a counter-balancing means during the period of such longitudinal movement. It will be understood, nevertheless, that the shaft is at all times subject to the stress of the counter-balancing means whereby it obtains a continual tendency to rotate or rather to re-

sist rotation in the direction of rotation of the drum. More explicitly still, the shutter drum is provided with a longitudinally shifting clutch element coacting with a clutch element carried by said drum and adapted to permit an initial gravity fall of the shutter and consequent rotation of the drum during the course of such longitudinal movement, whereby the counter-balancing means is over-balanced initially and the impetus gathered, together with the additional depending weight of the shutter, will carry the said shutter to lowered or closed position.

The preferred form of my invention is shown in the accompanying drawings, in which similar characters of reference designate corresponding parts, and in which:

Figure 1 is a vertical longitudinal section of my assembled fire door, shown in set condition, Fig. 2 is an end elevation of my invention showing the structure of mechanism for winding the counter-balance spring, Fig. 3 is an end elevation taken from the opposite end of my improved fire door and showing the automatically operative lever utilized, and, Fig. 4 is a detail of a section of the drum showing the clutch element preferably utilized by me.

The structure desirably comprises base elements 1 and 2 having journals 3 and 4 with reinforcing collars 5 and 6 embracing the same and one of said journals being longitudinally adjustable by means of a nut 7 threaded thereon at a point without the base element 2 and having an abutment collar 8 mounted upon the opposite and inner end thereof, the purpose of which will be hereinafter explained. Upon the outer surface of the base element 1, there is pivotally mounted a pawl 9 and upon the inner face of the said element is rigidly disposed a pierced lug 10. Upon the outer face of the base element 2, is provided a bifurcated bracket 11 between the legs of which is pivotally mounted a lever 12 having an aperture 13 near its free extremity.

Mounted in the journals 3 and 4 and concentrically disposed with relation to each other are shafts 14 and 15. The shaft 14 extends to a point without the base element 1 and is provided on its outer extremity with a rigidly secured ratchet wheel 16. Near its inner extremity there are mounted spaced collars 17 and 18 having, respectively, clutch teeth 20 and 21 which may be in

tegrally formed upon their opposing surfaces. The collar 18 is extended to a point beyond the inner extremity of the shaft 14 and this extension is concentrically socketed 5 as at 19 and, furthermore, embraced by a coil spring which is secured thereto, and which has its other end secured to the collar 8 upon the journal 4. The shaft 15 is loosely supported in the socket 19 and in its 10 journal; and it is further provided near its outer end with an abutting collar 22 and at its extreme outer end with a vertical socket 23.

A rotatable drum 24 is mounted upon the 15 journals 3 and 4 by means of the drum heads 25 and 26. Disposed within the said drum 24 near one end and rigidly secured thereto, is a disk member 27 having clutch teeth 28 and 29 respectively, disposed on 20 either side thereof; and, inasmuch as this disk is mounted between the spaced collars 17 and 18 and forms a journal for the shaft 14, there is permitted a complementary clutch action.

25 The coil spring above mentioned, is designated 30 and is normally distended and of an accumulated torsional stress. Cords 31 and 32 are connected, respectively, to the lug 10 and lever 12 at 13 and are joined by 30 a fusible link 33 which is of sufficient strength to maintain the lever 12 in the position shown and abutting the end of the shaft 15 to maintain it at its innermost position. Inasmuch as this shaft 15 is forced 35 into the socket 19 and thereby moves the collar 18 as far to the left as possible, the fusible link connection is the cause of the distended condition of the spring 30.

In operation, considering that the 40 elements are in the position shown in Fig. 1, an excessive heat causes the link 33 to weaken and break, and thereby separate the cord connections. When this happens, the distended spring immediately returns to normal 45 condition and draws the shafts 14 and 15 and collars 17 and 18 to the right, forcing the lever 12 outwardly. Before this movement, the collar 18 to which is connected the torsion spring 30, was in counterbalancing 50 relation with the drum 24 through the medium of the teeth 21 and 29. At the end of this movement, the collar 17 has been drawn into position to cause its teeth 20 to lock with the teeth 28; but, owing to the peculiar 55 relative location of the teeth on the disk 27 and collars 17 and 18, the drum is capable of a single complete revolution before these teeth 20 and 28 effect an interlocking connection. Thus it will be seen that the longitudinal shifting of the shafts 14 and 15, 60 although of short duration, is effective to momentarily release the counter-balancing spring 30 from its control of the disk 27 and consequently the drum 24. In this momentary release, the shutter mounted upon

the drum 24 attains sufficient impetus and added weight to overbalance the effect of the spring 30 and gradually move to lowered position. When it is desired to again tension the counter-balance spring 30, it is 70 only necessary to rotate the ratchet wheel 16 in an anti-clock-wise direction and maintain it at any tension by the pawl 33. It will be understood that the purpose of the abutting collar 22 is to limit the outward 75 movement of the shaft 15 to which it is rigidly secured.

What I claim, is—

1. An automatic fire shutter comprising a drum, a shutter carried thereby, a counter-balance means, and a shaft longitudinally shiftable to successively release and clutch said drum to said counter-balance means. 80

2. An automatic fire shutter comprising a drum, a shutter carried thereby, a counter-balance means, a shaft longitudinally shiftable, and a double clutch to successively release and connect said drum to said means. 85

3. An automatic fire shutter comprising a drum, a shutter carried thereby, a counter-balance means, a shaft longitudinally shiftable, a two-face clutch unit connected to said drum, complementary clutches controlled by the shifting of said shaft and rendered effective to successively unclutch and clutch 95 said means to said drum whereby said counter-balance means is rendered momentarily ineffective with relation to said drum.

4. An automatic fire-shutter comprising a drum, a shutter carried thereby, a counter-balance means, a clutch element upon said drum, and a complementary clutch element longitudinally shiftable from abnormal to normal position and connecting said counter-balance means to said drum in both positions, said shifting action causing a momentary ineffectiveness of said counter-balance means. 100

5. A gravity operated fire shutter comprising a base, a drum, an element longitudinally shiftable from abnormal to normal position, and a counter-balance means between said base and said drum, said means being effective in either of said positions but ineffective during its actual shifting operation. 110

6. A fire shutter comprising a drum, a shutter, counter-balance means for said shutter, a disk carried by said drum, clutch teeth on both faces of said drum, a shaft movable upon release by excessive heat from abnormal to normal position, a complementary clutch member on either side of said disk and carried by said shaft, one of said clutches being in co-active relation with one of the faces of said drum prior to release of said shaft, the other of said clutches being in co-active relation with the other face of said disk when in normal position, said counter-balance being permanently effective 120

125
130

to retard rotation of said shaft after its shifting movement.

7. A gravity fire shutter comprising a drum, a shutter, counter-balance means, a shaft longitudinally movable to which said counter-balance is permanently applied, a clutch within and carried by said drum, complemental clutch elements on said shaft and within said drum and coacting at either 10 end of said longitudinal movement with

said clutch to counter-balance said drum and shutter, said longitudinal movement causing a momentary release of said counter-balance means.

In testimony whereof I affix my signature 15 in presence of two witnesses.

THOMAS E. COLLINS.
